United States Patent

Des. 242,505
Patented Nov. 30, 1976

242,505

BASEBALL GLOVE

James Robert McTear, 32 Squadron Line,
Simsbury, Conn. 06070

Filed May 19, 1975, Ser. No. 578,591

Term of patent 14 years

Int. Cl. D2—06

U.S. Cl. D2—361

FIG. 1

FIG. 2

FIG. 1 is a front perspective view of a baseball glove showing my new design; and

FIG. 2 is a back perspective view thereof.

The characteristic feature of my design resides in the webbing portion shown.

I claim:

The ornamental design for a baseball glove, as shown and described.
